(57) **CLAIM**

The ornamental design for an indoor blind as shown and described.

DESCRIPTION

FIG. 1 is a top, front, left perspective view of an indoor blind.

FIG. 2 is a bottom, rear, right perspective view of the indoor blind shown in FIG. 1.

FIG. 3 is a front view of the indoor blind shown in FIG. 1.

FIG. 4 is a rear view of the indoor blind shown in FIG. 1.

FIG. 5 is a left-side view of the indoor blind shown in FIG. 1.

FIG. 6 is a right-side view of the indoor blind shown in FIG. 1.

FIG. 7 is a top view of the indoor blind shown in FIG. 1.

FIG. 8 is a bottom view of the indoor blind shown in FIG. 1.

FIG. 9 is a front view of an alternative configuration of the indoor blind shown in FIG. 1 in a closed position.

FIG. 10 is a front view of an alternative configuration of the indoor blind shown in FIG. 1 with the mesh of the indoor blind in a closed position; and,

FIG. 11 is a front view of an alternative configuration with the indoor blind shown in FIG. 1 in an open position.

The break lines shown in the figures symbolize breaks in the length of the article in which the claimed design is embodied. The appearance of any portion of the article between the break lines forms no part of the claimed design. The broken lines in the drawings illustrate the portions of the indoor blind that form no part of the claimed design.

1 Claim, 11 Drawing Sheets
